UNITED STATES PATENT OFFICE

167,548

HYDRAULIC PUMP

William F. Wanner, Minneapolis, Minn.

Application March 3, 1951, Serial No. 14,368

Term of patent 14 years

(Cl. D65—1)

To all whom it may concern:

Be it known that I, William F. Wanner, a citizen of the United States, residing at Minneapolis, county of Hennepin, and State of Minnesota, have invented a new, original, and ornamental Design for a Hydraulic Pump, of which the following is a specification, reference being had to the accompanying drawing, forming part thereof, and in which

Fig. 1 is a side perspective view of a hydraulic pump, showing my new design;

Fig. 2 is an elevational view of the left end shown on Fig. 1 on a slightly reduced scale; and

Fig. 3 is an elevational view showing the side opposite from that shown in Figure 1.

I claim:

The ornamental design for a hydraulic pump, substantially as shown.

WILLIAM F. WANNER.
